UNITED STATES PATENT OFFICE.

HORACE CAMMACK, OF DES MOINES, IOWA.

GEARING FOR WASHING-MACHINES.

933,692.

Specification of Letters Patent. Patented Sept. 7, 1909.

Application filed April 13, 1906. Serial No. 311,442.

To all whom it may concern:

Be it known that I, HORACE CAMMACK, a citizen of the United States, residing in Des Moines, in the county of Polk and State of Iowa, have invented certain new and useful Improvements in Gearing for Washing-Machines, of which the following is a full, clear, and exact description, reference being had to the accompanying drawings, forming part of this specification.

My invention relates to a gearing for operating the agitators of washing machines, and it has for its object to provide a simple and efficient construction of this character and one which includes a rack member for imparting rotary motion to the agitator, and means whereby the operation of said rack member is governed in a manner to cause it to constantly operate with uniform action with a slight expenditure of power in its operation.

Figure I is a top or plan view of my gearing. Fig. II is a side elevation of the gearing. Fig. III is a top or plan view of a modification. Fig. IV is a top or plan view of another modification. Fig. V shows a detail view illustrating the swivel joint for connecting the rack with the pitmen in the modified form shown in Figs. III and IV. 1 designates part of a washing machine, which may be of any ordinary construction and which may support or have incorporated therein a tub to receive the clothes to be washed by the agitator and gearing to be described.

2 is an agitator which is adapted to operate in the tub of the machine and which may be of any desired form or construction. The agitator is carried by a spindle 3 which is mounted in a bearing post and has a pinion 5 fixed thereto. The bearing post 4 is rigidly mounted upon the top of the washing machine to which it is secured in any suitable manner.

6 designates a reciprocating rack bar arranged in mesh with the pinion 5 and held in such position by stationary keeper arms 7.

9 is a hand lever to which the rack bar is pivoted at 8 and which is in turn pivoted at 10 to a bracket arm 11 that is fixed to a stationary part of the machine. The hand lever is supported by the bracket arm to which it is pivoted and it serves as an operating member for the reciprocating rack bar whereby said rack bar may be moved to and fro to impart rotary motion to the agi-

tator 2 due to the meshing of said rack bar with the pinion 5 on said spindle.

12 designates a bearing frame that is attached to the top of the washing machine. 33 This frame is provided with a pair of guides 13 between which the rack bar is adapted to operate and it is also provided with bearings 14 and 15 arranged in alignment with each other and occupying positions at right angles to the rack bar 6. The frame 12 also has a bearing arm 16 projecting outwardly therefrom and terminating in a bearing 17.

18 is a governor wheel journaled to the bearing 17 and provided with a wrist pin 73 19. 20 is a pitman loosely fitted at one end to said governor wheel wrist pin and pivoted at its other end to the rack bar 6 at 21.

22 is a pinion that is arranged in mesh with the governor wheel and which is carried by a fly wheel shaft 23 that is supported by the bearings 14 and 15 and has fixed thereto a fly wheel 24.

In the practical use of my gearing the operation is as follows: The operator grasps 30 the hand lever 9 and by rocking it to and fro imparts a reciprocating movement to the rack bar 6 and said rack bar by meshing with the pinion 5 serves to impart a rotary motion to the agitator 2. During the reciprocation of the rack bar the pitman 20 is moved longitudinally to and fro and by reason of its pivotal connection with the rack bar and the governor wheel it serves to impart rotation to the governor wheel. The 35 rotary motion of this wheel is transmitted to the pinion 22 and the pinion in turn serves to drive the shaft 23 and the fly wheel 24 fixed to said shaft. It will be seen that by this arrangement of the governor wheel and the fly wheel operatively connected with each other, and the governor wheel being connected to the reciprocating rack bar by the pitman 20, said fly wheel and governor wheel are caused to control the movement of the 40 rack bar whereby it will reciprocate with an even and regular motion and with a slight expenditure of power after the gearing is once placed in motion.

In the modification illustrated in Fig. III, 135 the pinion of the agitator spindle is operated by a segmental rack 6' which is carried by a swinging arm 6'' that is pivoted at its end farthest from the rack at 28. The swinging arm is vibrated through the medium of a 110 connecting rod 29 that is united to the rack arm 6'' by a swivel 30 and attached to the

hand lever 9 by a coupling member 31. The pitman 20' is connected to the swivel 30 and is attached to the governor wheel 18' by a swivel wrist pin 19'. The parts illustrated in Fig. III are adapted to have associated therewith the fly wheel, its shaft and pinion which operate in connection with this modification in the same manner as previously described with respect to the main form of gearing.

The modification shown in Fig. IV differs from the modification shown in Fig. III only in the respect that the pivotal point of the vibratory rack bar arm 6'' is located intermediate of the ends of the arm instead of at its end, and the connections leading to said arm are united thereto at its end farthest removed from the rack 6' instead of at the end at which the rack is located.

One of the advantages of having an upright lever fulcrumed to the body of the machine and provided with a pitman moving in a direction toward and from the central portion of the body is that when starting the device, the operator may forcibly push the lever toward the central portion of the body without there being any tendency to tilt or upset the machine body.

Another advantage gained by the use of my improved gearing device is that by having the large gear wheel connected with and operated by the rack, the said large gear wheel may be disposed upon the machine body in a convenient position with regard to the operating lever and to the other parts of the device, and this statement is true even though different forms of racks for operating the agitator shaft are used, as is illustrated in the various modified forms shown in the drawings.

Another advantage is gained by the employment of a universal joint or swivel for connecting the racks, shown in Figs. III and IV with the pitmen that are attached to the large gear wheel, this advantage being that the large gear wheels may be arranged in any desired position with relation to the racks. Hence, by means of my improved gearing device, the operator, in assembling the mechanism may employ either of the kinds of racks shown and, by the use of the swivel joint connecting the rack with the pitman that is attached to the large gear wheel, he may arrange the large gear wheel on the machine body in the most convenient position and without having the gear wheel operate in a plane parallel with the movement of the rack. For instance, in Figs. III and IV, the rack swings in a horizontal plane and the gear wheel rotates in a vertical plane.

I claim:

1. A gearing device of the class described, comprising a support, an upright shaft mounted in the support, a pinion thereon, a lever fulcrumed

to the support below the upper end of said shaft, means connected with the lever and shaft for imparting an alternating rotary motion to the shaft by means of a reciprocating motion applied to the lever, and a governing device for the shaft, including a balance wheel, a speed increasing gearing, and a pitman, the latter being connected to the speed increasing gearing and also to the said means for operatively connecting the lever and shaft.

2. A gearing device of the class described, comprising a support, an upright shaft mounted in the support, a pinion thereon, a rack in mesh with said pinion, a lever fulcrumed to the support, a pitman connecting said lever and rack for imparting an alternating rotary motion to the shaft by means of a reciprocating motion applied to the lever, and a governing device for the shaft, including a balance wheel, a speed increasing gearing, and means operated by said rack for imparting a continuous, rotary motion to the speed increasing gearing.

3. A gearing device of the class described, comprising a support, an upright shaft mounted in the support, a pinion thereon, means for imparting an alternating rotary motion to the pinion, said means comprising a lever fulcrumed to the support, and a rack in mesh with the pinion and operatively connected with the lever, and a governing device, comprising a balance wheel, a speed increasing gearing, and a device for operatively connecting the speed increasing gearing with the means for operating the said pinion, said connecting device being provided with parts capable of universal movement relative to each other, whereby the parts to which said connecting device is attached may move in divergent planes.

4. A gearing device, comprising a support, an upright shaft mounted in the support, a pinion thereon, a lever fulcrumed to the support below said pinion, a rack connected with the lever and in mesh with said pinion, and a governing device for the shaft comprising a balance wheel, a small gear wheel connected with the balance wheel, a large gear wheel in mesh with the small one, and a pitman connected to the large gear wheel and also connected with said rack, for the purposes stated.

5. In a gearing, the combination of an upright shaft, a pinion thereon, a horizontally movable rack meshed with the pinion, a governing means including an upright governing wheel, and a pitman connected with the horizontally movable rack, and an operating means comprising an upright lever connected with the rack.

6. In a device of the class described, the combination of an operating lever, an upright shaft, a pinion thereon, a rack pivoted to the lever and in mesh with said pinion,

a vertically arranged governing wheel, a vertically arranged fly wheel, a pinion connected with the fly wheel and in mesh with the governing wheel, and a pitman pivotally connected to the rack and to the said governing wheel.

7. In a gearing, the combination of a pinion, a rack member geared to said pinion, means for operating said rack member, a 10 governor wheel, a pitman connecting said rack member to said governor wheel, a fly wheel shaft, a fly wheel fixed to said shaft and a pinion fixed to said shaft and arranged in mesh with said governor wheel, substantially as set forth.

8. In a gearing, the combination of a pinion, a reciprocatory rack bar arranged in mesh with said pinion, a hand lever for operating said rack bar, a governor wheel, 20 a pitman connecting said governor wheel to

said rack bar, a fly wheel shaft, a fly wheel fixed to said shaft, and a pinion fixed to said shaft and arranged in mesh with said governor wheel, substantially as set forth.

9. In a gearing, the combination of a 25 pinion, a reciprocatory rack bar arranged in mesh with said pinion, guides for directing the travel of said rack bar, a hand lever having pivotal connection with said rack bar, a governor wheel, a pitman connecting said 30 governor wheel to said rack bar, a fly wheel shaft, a fly wheel fixed to said shaft, and a pinion fixed to said shaft and arranged in mesh with said governor wheel, substantially as set forth.

HORACE CAMMACK.
